UNITED STATES PATENT OFFICE.

AITKEN FRANKHAUSER, OF NEW YORK, N. Y.

WINDOW-CLEANING DEVICE.

1,070,676.

Specification of Letters Patent. Patented Aug. 19, 1913.

Application filed May 22, 1911. Serial No. 628,742.

To all whom it may concern:

Be it known that I, AITKEN FRANKHAUSER, a citizen of the United States, residing at the city of New York, in the borough of Brooklyn, county of Kings, and State of New York, have invented a new and useful Window-Cleaning Device, of which the following is a specification.

This invention relates to improvements in that type of cleaning devices which may be attached to the front windows or glass shields of street cars, locomotive cabs, pilot houses, automobiles or other conveyances used for traveling, and of certain stationary structures as well, to remove therefrom any moisture, rain, snow, sleet, frost or such matter as may gather or be precipitated upon the window panes and would obstruct the view of the driver, motorman, engineer, pilot, chauffeur or other attendant, as the case may be. Reference is had particularly to devices wherewith part of the surface of a window-pane can be cleaned on the outside by operation from within, the same being of sufficient area to give a full, unobstructed view of objects ahead, to an observer located on the inside.

The principal object of the invention is so to construct the device that it may be applied to do the cleaning with a greater or less degree of pressure dependent upon the will and action of the operator, guided by atmospheric conditions and attending circumstances wherever he may be stationed or moving.

Other objects are to provide a cleaner of the type set forth which will be of simple as well as effective construction, easily attached or detached, and capable of economical renovation.

I attain these objects by the mechanism illustrated in the accompanying drawing, in which—

Figure 1 shows a transverse horizontal section of a window sash, on which this improved cleaner is mounted, ready for operation, and Fig. 2 is a substantially central cross-section of the device separate from the sash taken on the line 2—2 of Fig. 1.

Similar letters refer to similar parts in both views.

A bushing *a* is inserted in the window sash or other convenient point at such point that the device will not prevent the sliding of the sash to one side, or raising or lowering it as the case may be; into said bushing *a*

is inserted from within an operating lever *b* extending beyond the bushing. The inner end of this lever is bent parallel to the window pane and forms a handle by means of which the device is manipulated, it being spaced from the pane a suitable distance for the purpose. The middle portion is cylindrical where it passes through the bushing, to enable it to be rotated or rocked therein. 60 Beyond this cylindrical portion, the lever is squared and made to project away from the sash on the outside. Over the end of the operating lever is set an arm *c*, which is made to extend also parallel to the window pane, on the outside, preferably as far as the center thereof and opposite the said lever handle. A curved spring “*d*” is placed over the socket part of this arm, and held thereagainst by a pin “*e*” passing 65 transversely through the outer end of the squared portion of the lever. This spring, tends to draw the lever outward, causing a shouldered portion thereof to bear firmly upon a peripheral flange of the bushing “*a*.” 70 The other end of the arm *c* has offset jaws *f f* turned edgewise toward the window pane and through which a bolt or pin “*g*” is placed at right angles to the length of said arm. 75

Extending the length of and beyond the arm *c* and held in the jaws *f f* by the bolt *g* is the window cleaner *h* consisting of two metal strips *i i* and between them a rubber strip or other pliable material *k* which extends slightly beyond the metal strips on the side next the window, the metal and rubber strips composing the cleaner being riveted or screwed together, said window cleaner *h* has a hole through the center adapted to receive the pin “*g*” and countersunk at *l l* on both sides to permit of the cleaner being inclined at will of the operator, the cleaner being normally poised or held in vertical position for wiping off moisture, dust, etc. 80 by the rubber only, by two springs *m m* set between the sides of the cleaner and the jaws *f f*. The pin *g* may be prevented from endwise movement relative to the jaws *f f*, by any approved means, for instance by 85 pins *p p*.

The operator, by pulling the lever *b* inward causes the rubber strip to adhere to the window glass, and by moving the same arcuately in either direction, the whole 90 cleaner inclines or tilts to either side where the resistance is the least, being permitted

to do so by the countersunk holes at l l , the giving way by one of the springs m m , and the jaws f f being wide enough to admit of the necessary inclination. Either edge of 5 the metal strips may then be brought into dragging contact with the surface of the window glass with sufficient pressure to cut or scrape away any sleet, frost or other hard substance that may gather thereon. The 10 said jaws "f" are suitably spaced apart to admit of the aforementioned tilting of the strips "i" "k" and corresponding flexure of their springs "m" m , and further they are narrowed inwardly as represented at "f" 15 in Fig. 2, to form abutments, which limit the movement of the strips or plates "i" in both directions sidewise on the pin g .

I claim:

1. A window cleaning device comprising 20 an element adapted to be moved over the surface of the glass pane, means for yieldingly supporting said element whereby it will normally be maintained in a position substantially perpendicular to said surface, 25 and actuating means capable of moving the element toward the pane and swinging it across the same either in its normal position or tilted, so as to produce a dragging motion, at the will of the operator.
2. A window cleaning device comprising 30 an element composed of both soft and hard materials, an arm normally holding said element with the soft material thereof in contact with the glass pane, a depressor where- 35 by the arm can be carried inward to tilt said element and cause it to sweep the pane with both its said hard and soft materials and resilient means connected with said depre- 40 sor and the arm.
3. A window cleaning device comprising an operating lever fitted to oscillate in the window sash, said lever being shouldered to bear on one side thereof, an arm located on the opposite side, a cleaning element com- 45 posed of both soft and hard materials carried by said arm with the soft material touching the glass pane and the hard material spaced therefrom, and a yielding con- 50 nection tending to draw said arm toward the window, said cleaning element being tilt- 55 ably connected to the arm to allow both said hard and soft materials to touch the glass pane when the arm is drawn inwardly to full extent.
4. A window cleaning device comprising 55 an element composed of soft and hard mate- rials, the soft material normally contacting

edgewise with the window pane and the hard material being set back a short distance therefrom, an arm adapted to move said 60 element across the surface of the pane, a pivot pin on which said element is tiltably hung from said arm, said element having oppositely flaring holes through which said pivot-pin is passed, a handle for actuating 65 said arm allowing it to be drawn with the element toward the pane's surface, and means for normalizing the element after tilting.

5. A window-cleaning device comprising 70 an element normally touching the glass pane perpendicularly, an arm adapted to move said element, jaws on the arm between which said element is tiltably mounted, a spring operating to normalize the element after it 75 has been tilted, means on the jaws for limit- 80 ing the tilting movement of the element, and actuating means whereby the arm can be moved with the element tilted to cause either edge thereof to contact the pane with a 85 dragging motion.

6. A window cleaning device comprising 85 an element composed of combined flexible and rigid material, the flexible material be- 90 ing set normally to touch the glass pane alone with the rigid material slightly receding therefrom, an arm adapted to carry said element across the pane, a pair of jaws on said arm, a pivot pin running transversely of said jaws, said element having opposite 95 outwardly flaring holes through which said pivot pin passes, and which enable it to be inclined either way thereon, a pair of springs between said jaws tending to main- 100 tain said element perpendicularly to the window glass, an operating stem passing through and fitted in the window sash, said stem being shouldered to bear on one side of said sash and projecting beyond the other side thereof, said arm being attached to the projecting end of said stem so as to be moved thereby, a compression spring upon the stem and the arm carrying said element, and a handle formed on the stem whereby 105 it can be moved with or without compressing said spring, thus enabling the operator to move the cleaning element at his option either tilted or perpendicular arcuately over the surface of the window pane.

AITKEN FRANKHAUSER.
